UNITED STATES PATENT OFFICE.

JOSEPH ARMSTRONG, OF ALLSTON, MASSACHUSETTS, ASSIGNOR TO AMERICAN MOISTENING COMPANY, OF BOSTON, MASSACHUSETTS, A CORPORATION OF MAINE.

PORTABLE PSYCHROMETER.

Application filed August 31, 1926. Serial No. 132,688.

This invention relates to improvements in portable psychrometers. More especially it relates to instruments of this sort in which a fan is employed to drive a blast of air past the thermometer bulbs and has to do particularly with the provision of manually actuated mechanism for rotating the fan.

In the working of fibrous materials, such as cotton and wool for example, it is highly important that the air coming in contact with these materials be tempered with the proper amount of entrained moisture. Humidifying apparatus is available for supplying this moisture and control devices have been developed for regulating their moisture discharge in accordance with the air conditions existing at the location of the control units. The latter, however, are usually mounted in some central or "average" location in a room where there is a convenient support and it is not unusual to find that the air conditions there are not the same as those of the region closely adjacent to the material being worked. It is accordingly desirable to test the air conditions at various locations more or less remote from the control devices and in greater proximity to the material itself. The present invention is directed to the provision of a psychrometer which can be carried in hand to any location, and there held stationary while a continuous blast of the air being tested is driven past the wet and dry bulbs of its thermometers.

It is an object of the present invention to provide a simple compact device in which there is a fan for moving the air past the bulbs and mechanism by which the power of the tester's thumb or finger is utilized to effect rotation of the fan. It is a feature of the device that when the wet and dry bulb temperatures have been determined the percentages of relative humidity and cotton or wool regain, corresponding to those temperatures, can be readily ascertained from an integrating device mounted on the instrument.

These objects are attained by mounting a pair of thermometers at the front of a vertically extending casing which rises from a hollow base that serves as a reservoir for water. The latter is carried to the bulb of one of the thermometers by a wicking encasing the bulb. A rotatable fan is set within the casing in position to blow a sample of air

uniformly past both the wet and dry bulbs. The casing has an external handle at the rear by which the instrument can be supported in one hand, and close by the handle is a rod which can be pushed downward by the thumb or a finger of that hand. This rod is part of power transmission mechanism whereby the linear motion imparted to the rod is transformed into rotary motion of the fan. A ratchet mechanism permits a spring to return the rod to starting position ready for another push downward by the operator while the momentum of the fan continues it in motion. Thus a sample of air is caused to blow uniformly past both thermometer bulbs, gradually lowering the temperature of the wet bulb thermometer in accordance with the amount of moisture the passing air is able to take up from the wicking.

On the front of the casing, between the thermometers, is an integrating device having a movable element which can be set in accordance with the wet and dry bulb temperature readings of the thermometers. When thus set, the percentages of cotton regain, relative humidity and wool regain corresponding to the said temperatures will be indicated simultaneously by the device.

It is intended that the patent shall cover by suitable expression in the appended claims whatever features of patentable novelty exist in the invention disclosed.

In the accompanying drawings:

Figure 1 is a front elevation of a portable psychrometer embodying the present invention;

Figure 2 is a side elevation, in medial section on line 2-2 of Figure 1;

Figure 3 is a plan, on line 3-3 of Figure 2, but with most of the base cut away;

Figure 4 is an elevation on line 4-4 of Figure 2, of the lower end of the push rod and connected gearing;

Figure 5 is an elevation like Figure 4, but on line 5-5 of Figure 2, showing the mechanism as seen from the front; and

Figure 6 is a rear view of the instrument.

Referring to the drawings, a casing 10 has a hollow base 12 holding a supply of water which may be poured into it through an opening normally closed by screw cap 16. Two thermometers 18 and 20, one for registering the dry bulb temperature and the other for registering wet bulb tempera-

ture, are mounted in grooves formed by side strips 10^a and 10^b fastened to the front edges of the side walls 10^c. The bulb of each thermometer extends below its supporting strip to near the bottom of the casing behind a perforated cover plate 22. The bulb 20^a of the wet thermometer is encased within a wick 26 which extends into the reservoir base 12 and by capillary action feeds moisture to the region of the bulb where it is evaporated by the air around it. This air in the immediate vicinity of the wet bulb soon becomes more or less saturated and cannot then absorb moisture as fast as would the air further removed from the bulb; in fact the entire air within the casing becomes slightly moistened and as a result the dry bulb thermometer actually reads lower than the temperature of the air outside the casing and the wet bulb thermometer reading is higher than that showing true wet bulb depression. In order to insure accurate readings of the two thermometers there is provided a fan 28 set to draw outside air through an opening 29 in the back of the casing, and blow it uniformly across both bulbs and out through the perforations 24 in the front cover plate. Thus a continuous stream of the air to be tested affects both thermometers, causing the dry bulb instrument to show the actual temperatures of the air and the other thermometer to show the temperature corresponding to the wet bulb depression for that air. The latter is of course dependent upon the actual humidity in the air and the amount of moisture that can be absorbed from the wick.

A handle 30 is provided on the back of the casing by which the psychrometer can be held in the hand at any desired location. The upper end 30' of this handle projects through an upper opening 32 in the back wall and forms a bearing for a rod 34 which has a button 34^a on its upper end in position to be pressed conveniently by the operator's thumb or finger. The lower end of this rod is forked and straddles a raised strip 36 which is pressed outward from a disk 38 and serves to guide the rod in its linear travel. The disk is mounted on a depending plate 40 attached to the casing by the same means 42 that clamps the lower end of the handle thereto, and is thus positioned centrally of the opening 29.

On the raised guide strip 36 is secured a small plate 46 which overlies the forked prongs 34^b of the push rod and keeps the latter from moving away from the face of the disk. A spring 48 anchored to this plate and attached to one of the prongs serves to pull the rod upward when the pressure of the thumb is released at the end of a down stroke. The outside edge of one of the prongs 34^b is provided with teeth and thus

constitutes a rack which meshes with a small pinion 50 supported on a shaft 52 having one bearing in the disk 38 and the other in a bracket 54 mounted on one edge of the disk with its arm 54^a extending across it. On this shaft 52, and secured to the small pinion 50, is a ratchet wheel 54 whose teeth are cut with a driving face on one side and a cam face on the other. A larger gear 56 is also journaled on the shaft 52 beside the wheel 54 and carries on its side a pivoted pawl 58 which is in the plane of the ratchet wheel. When the latter is rotated in one direction by downward thrust of the push rod, the driving face of one of its ratchet teeth 80 engages the pawl and causes the large gear to turn with it, and since the latter meshes with a small gear 60, fast on the fan shaft 62, the fan is also rotated. When the rod 34 is moved upward by the spring 48, the cam 85 faces of the ratchet wheel teeth slide freely by the pawl, allowing the fan to continue to rotate under its momentum. Before it comes to rest another downward stroke of the push rod occurs and thus the fan is kept continuously in rotation by the operator successively pushing the rod downward as it is returned by the spring.

The psychrometer can be carried to any location where a test is desired, and by simply pushing down on the rod, as explained, a continuous stream of air can be passed simultaneously over both the wet and dry bulbs. At first their readings will change, the dry temperature slightly rising and the wet temperature falling. When the mercury in both thermometers stands still the reading of each is taken and, by means of an integrating device mounted on the instrument, the percentages of relative humidity 100 and cotton or wool regain can be quickly determined.

This device comprises a scale plate 64 arranged on the front of the casing between the grooved strips 10^a and 10^b. This plate 110 has turned over edges which lie behind the inner edges of the grooved strips and form guides for a sliding element 66. A slot 64^a is cut centrally of the scale plate and on one of its edges is laid out graduations 68, from 115 50° to 110° for example, corresponding to the graduations of the wet bulb thermometer. On the sliding element 66, adjacent the graduations 68 and visible through the slot 64^a are similar graduations 70 laid out to 120 represent the degrees of the dry bulb thermometer. On the other edge of the slot 64^a are three sets of graduations, one 72 representing percentages of cotton regain, another 74 representing percentages of relative 125 humidity, and the third 76 representing percentages of wool regain. In proper relation to these three sets of graduations on the fixed scale plate are three arrows or indicators 78 on the sliding element. 130

When the readings of the thermometers are taken the sliding scale is moved until the graduation thereon corresponding to the dry bulb temperature is set opposite the graduation of the fixed wet bulb scale which corresponds to the wet bulb temperature. The percentages of cotton regain, of relative humidity and of wool regain, corresponding to the temperature readings, are then indicated 5 simultaneously by the three arrows 78 on the respective scales 72, 74 and 76.

The convenience of the psychrometer is obvious. It can be used anywhere that a hand can hold it. It is not dependent upon 10 a source of power other than the operator's muscular efforts. And because it employs no other power means, as for example an electric motor, there is no danger of the lead wires becoming entangled in the fibrous material and no fire hazard from the sparks of such a motor. The device is simple, can be manufactured at small cost, and is accurate 15 in operation. It determines the dry and wet bulb temperatures and enables the tester 20 to ascertain from these the desired characteristics of the air being tested.

I claim as my invention:

1. A psychrometer comprising, in combination, a casing having a reservoir for water 30 in its base; a pair of thermometers mounted on the front wall of said casing; a wick extending from said reservoir around one of the thermometer bulbs; a fan arranged in said casing for blowing air to be tested past both bulbs; a handle on the back of said casing whereby the psychrometer can be held in the hand; a push rod arranged with respect to said handle to enable the rod to be actuated by the hand holding the psychrometer; and power transmitting connections 35 between said rod and the fan for transforming the linear movement of said rod into rotative movement of the fan.

2. A psychrometer comprising, in combination, a casing having a pair of thermometers mounted thereon; means for supplying moisture to the bulb of one thermometer to be evaporated therefrom; a fan arranged within said casing for blowing air to be 40 tested past the thermometer bulbs; means for holding said casing in the hand; and power

transmission means having operative connection with the fan and adapted to receive power impulses from the hand and transmit them to the fan, comprising a rod adapted 55 to be engaged by the hand and having teeth along its edge, a train of gearing meshing with the teeth on said rod and adapted to cause rotation of said fan.

3. A psychrometer comprising, in combination, a casing having a pair of thermometers mounted thereon; means for affecting said thermometers whereby they will show respectively wet and dry bulb temperatures; and means on said casing interposed between 60 said thermometers comprising a scale plate having graduations corresponding to the 65 graduations on one of said thermometers and other graduations laid out in relation thereto corresponding to percentages of the 70 characteristic property of the air to be determined; another scale movable with respect to said scale plate having graduations thereon arranged in accordance with the 75 graduations of the other of said thermometers and having an indicator arranged to indicate on the percentage graduations the characteristic property of the air when said thermometer scales are positioned with their graduations corresponding to their respective 80 thermometer readings opposite to one another.

4. In apparatus for registering wet and dry bulb temperatures, the combination with the thermometers thereof of integrating means consisting of four stationary scales 85 with graduations corresponding to wet bulb temperatures, cotton regain, relative humidity, and wool regain percentages respectively, and a sliding scale with indications corresponding to dry bulb temperatures and 90 adapted to be moved relative to the stationary scales; there being three pointers on said slideable scale adapted to indicate conditions of the air on said percentage scales when the graduation on the sliding scale corresponding to the existing dry bulb temperature is made to register with the graduation on the wet bulb stationary scale corresponding to the existing wet bulb temperature. 95
